United States Patent Office

Des. 215,391
Patented Sept. 23, 1969

215,391

COMBINED SHEET AND EYELINERS

Leon J. Mitchell, 74 Forest Road, Dalston,
London, England

Filed Aug. 5, 1968, Ser. No. 13,024

Term of patent 14 years

Int. Cl. D28—02

U.S. Cl. D86—10

FIG.1

FIG.2

FIG.3

FIG.4

FIG.5

FIG. 6

FIG. 1 is a top plan view of a combined sheet and eyeliners showing my new design;

FIG. 2 is a bottom plan view; and

FIG. 3 is an edge view thereof;

FIG. 4 is a top plan view of a second embodiment of the design shown in FIG. 1;

FIG. 5 is a bottom plan view; and

FIG. 6 is an edge view thereof.

I claim:

The ornamental design for a combined sheet and eyeliners, substantially as shown and described.
